ATTORNEYS

UNITED STATES PATENT OFFICE.

EARL WOODRUM, OF GLENCOVE, WASHINGTON.

PICKING-BAG.

1,270,354.

Specification of Letters Patent. Patented June 25, 1918.

Application filed June 20, 1917. Serial No. 175,838.

To all whom it may concern:

Be it known that I, EARL WOODRUM, a citizen of the United States, and a resident of Glencove, in the county of Pierce and 5 State of Washington, have invented an Improvement in Picking-Bags, of which the following is a specification.

My invention relates to improvements in 10 picking bags, especially apple picking bags, and it consists in the combinations, constructions and arrangements herein described and claimed.

An object of my invention is to provide a 15 bag having a mouth which is held open by a metal loop at its upper end, the lower end of the bag being open but being provided with a drawing string by means of which the lower open end may be drawn together, and having a hook secured to the metal loop 20 through which the string may be passed and firmly secured, thereby permitting the bottom of the bag to be raised and fastened at any position, thereby preventing the escape of fruit through the bottom of the 25 bag.

Another object of my invention is to provide a device of the type described which may be quickly unfastened so as to permit the lowering of the bottom of the bag to increase 30 the capacity of the bag.

A further object is to provide a draw string which is free from knots, and which, therefore, is not dependent upon the engagement of a knot of the string for the successful 35 holding of the string in the hook.

A still further object is to provide a novel form of suspending means for the bag which insures the proper position of the bag on the body of the user at all times.

40 Other objects and advantages will appear in the following specification and the novel features of the invention will be particularly pointed out in the appended claim.

My invention is illustrated in the accompanying 45 drawings forming a part of this application, in which—

Figure 1 is a perspective view showing the bag in operative position.

Fig. 2 is a perspective view of the lower 50 portion of the bag showing the draw string in position.

Fig. 3 is a view of the lower portion of the bag showing the draw string drawn up to close the mouth of the bag.

55 Fig. 4 is a perspective view of the holding hook.

In carrying out my invention I provide a bag or container 1, which may be made of any suitable material, such as canvas, having its upper end held open by a loop of 60 metal 2 made in the shape shown in Fig. 1. It will be observed that this loop is curved on one side to fit the body and on the other side is bowed outwardly. Preferably the material of the bag is brought up over the 65 metal loop so as to cover it. On the bowed side, that is to say on the outer side of the bag, is a hook 3 like that shown in Fig. 4, this hook having a space 4 between the body portion and the bent up end which is relatively narrow. The hook may be made integral with the metal loop 2, or may be secured to it.

The bottom portion of the bag is shown in Figs. 2 and 3. It is open and is provided 75 with a draw string 6. This draw string is secured to the bag at a point 7 at the center of the bag near the bottom thereof. It will also be observed that this string is secured to the bag on the side of the bag next to the 80 body of the user. The two ends of the string are passed through eyelets 8 and continue on through eyelets 10 in strengthening tabs 11 which are secured to the edges of the bag, the ends of the string being free.

85 The bag is suspended from the shoulders of the user by a pair of straps 12, which are crossed over the wearer's back after the manner of ordinary suspenders, and each strap is provided with a snap hook 13 which engages a ring 14. Small suspending straps 15 connect the rings 14 with that portion of the loop 2 next to the body of the wearer, while other suspending straps 16 connect the bowed portion of the loop with the rings 90 14, the connections of the straps 15 and 16 with the loop 2 being such that the straps will not slip on the loop but will remain permanently in position.

95 From the foregoing description of the 100 various parts of the device the operation thereof may be readily understood. Fig. 2 shows the position of the bag when empty. The user of the bag first pulls on the ends of the draw string 6, thus partially closing the open end of the bag, in the manner shown in Fig. 3. The end is then raised, that is to say bent back upon the body portion of the bag, and suspended by doubly wrapping the ends of the string 6 around 110 the hook 3. The bag is then in the position shown in dotted lines in Fig. 1. It will be

observed that the end of the bag is drawn clear up to the hook 3. This reduces the capacity of the bag to its minimum, so that in picking apples, for instance, they will 5 not have far to fall. Now as the bag is gradually filled one may let out the string 6 by merely unwrapping it and then rewrapping it around the hook so that the top of the layer of fruit may be maintained at substantially a uniform distance from the upper edge of the bag until the bag is well 10 filled. I have stated that one purpose of this invention is to do away with knots in the string 6. Elimination of the knots permits the lower end of the bag to be drawn tighter, that is to say to be drawn into a smaller compass than if the string were knotted, but, perhaps, a more important feature is that the present construction permits 15 the lower end of the bag to be drawn clear up to the hook, which a knotted string would not permit. The feature of securing the string at any point is also an advantage, since one does not have to take the string 20 out of the hook to do this. All that is necessary is to unwrap one hitch and then to pull on the string until the right position is reached, whereupon the wrapping of the string around the hook once will hold the bag securely, even when the bag is full of 25 fruit. In fact the greater the weight the more securely will the string be secured to the hook.

The means for suspending the bag keeps 30 the mouth of the latter in a substantially horizontal position no matter whether the user leans forward or backward, since the hooks 13 will slide in the rings 14. Moreover the suspending members 15 and 16 are 35 so arranged that they hold the bag securely 40

without interfering with the movements of the user. It will be observed that these suspending members are placed far over toward the side of the bag, but there are two suspending members for the front as well as 45 for the rear, so that the bag is firmly supported.

When the bag is filled it is only necessary to unwrap the string from the hook and lower the string, when the weight of the 50 fruit will cause the mouth of the bag to spread open. It will be observed that the string 6 is secured to one side of the bag only so that the bag will instantly open under the weight of the fruit, as stated. 55

I claim:

A picking bag comprising a body portion having open upper and lower ends, a stiffening loop for maintaining the upper end in open position, a hook carried by the loop, 60 the end of the hook being bent back upon the body portion thereof to provide a relatively narrow space between the end and the body portion, a draw string secured to the central portion of the bag near the bottom on one side of the bag, strengthening tabs having eyelets, said strengthening tabs being disposed at the opposite edges of the bag, eyelets carried by the bag between said 65 strengthening tabs and the point where the string is secured, the ends of the string passing through said last-named eyelets and then through the eyelets in the strengthening tabs for drawing the lower end of the bag together, said string being adapted to be wound about the hook at any point between the strengthening tabs and the ends of the 70 string for frictional suspension from the hook. 75

EARL WOODRUM.
